REBREATHER APPARATUS

Frederick A. Parker, Broomall, Pa., assignor to
Biomarine Industries, Inc., Devon, Pa.

Filed May 11, 1973, Ser. No. 359,561

Term of patent 14 years

Int. Cl. D24—04, 99

U.S. Cl. D83—1 G

FIG. 1

FIG. 6

FIG. 7

FIG. 2

FIG. 3

FIG. 4

FIG. 5

FIG. 1 is a front perspective view of a rebreather apparatus showing my new design;

FIG. 2 is an elevation view of the left side as viewed from the front thereof;

FIG. 3 is a front elevational view thereof;

FIG. 4 is a top plan view thereof;

FIG. 5 is a bottom plan view thereof;

FIG. 6 is a rear elevation view thereof; and

FIG. 7 is an elevation view of the right side thereof.

The broken lines in FIG. 1 are shown for illustrative purposes only.

I claim:

The ornamental design for a rebreather apparatus, substantially as shown and described.
